UNITED STATES PATENT OFFICE

LEONARD W. LANGFORD, OF NORWELL, AND HARRY C. YAEGER, OF SHREWSBURY,
MASSACHUSETTS, ASSIGNORS TO LANGFORD SALES AUDIT MACHINE COMPANY, OF
BOSTON, MASSACHUSETTS, A CORPORATION OF MASSACHUSETTS

RECORD FEEDING MECHANISM

Original application filed February 21, 1928, Serial No. 255,963. Divided and this application filed July 9, 1929. Serial No. 377,022.

This application is a division of tabulating machine application Serial No. 255,963, filed February 21, 1928, and relates particularly to the record feeding mechanism thereof.

5 These records may be either in strip form as shown in a co-pending application to L. W. Langford, Serial No. 220,243 filed September 17, 1927, or individual cards formed by shearing the strip between the independent records. 10 The records are fed intermittently for the purpose stated in the parent application or for any other desired purpose. The primary object of the invention is to provide a feeding mechanism which is adapted to feed records in either strip or individual card form and to feed the same intermittently.

Each record on which our machine is adapted to operate is provided with a pair of location holes therein and it is another object of 20 our invention to provide a novel mechanism for accurately feeding these records intermittently, either individually or in strip form, and to keep the records properly located through the agency of these location holes.

Another object of the invention is the provision of means for stopping the record feed without stopping the operation of the record feeding means.

30 With the above and other objects in view our invention consists in the features of construction and operation set forth in the following specification and illustrated in the accompanying drawings. In such drawings we have illustrated certain embodiments of our invention but it will be understood that the invention can be otherwise embodied and that the drawings are not to be construed as defining or limiting the scope of the invention, 35 the claims appended hereto being relied upon for that purpose.

Referring to the figures of the drawings:

40 Fig. 1 is a fragmentary plan view of the machine showing our novel record feeding mechanism.

Fig. 2 is an enlarged sectional view taken on line II-II of Fig. 1.

50 Fig. 3 is a fragmentary detail view of the feed stopping mechanism.

Fig. 4 is a vertical sectional view through the machine on line IV-IV of Fig. 1.

Fig. 5 is a vertical sectional view on line V-V of Fig. 1.

Fig. 6 is a vertical sectional view on line VI-VI of Fig. 1.

Fig. 7 is a sectional detail taken on line VII-VII of Fig. 6.

Fig. 8 shows a strip of records adapted to be fed by the machine.

Fig. 9 shows a plurality of individual cards arranged in the feeding order.

The feeding mechanism is mounted on a shelf 1 supported on another shelf 2 hung on flanges 3 of the frame 4 supported by legs 5. The feed box 6 is an independent unit embodying vertical side plates 7 and a horizontal feed plate 8. The plate 8 is supported by a pair of L-bars 9 secured to and extending horizontally along the inner faces 65 of the side plates 7. Transverse bars 10 secured to the bars 9 serve to anchor the side plates to each other.

A record feeding channel 11 is formed between the plate 8 and a plate 12 secured to the bars 10. The record is entered at a 70 guide chute 13, passes through the channel 11, and emerges from the machine at 14.

The record is fed through the channel 11 by means of a plurality of record feeding 80 means relatively spaced along the channel in a manner to pass the record from one feeding means to the next adjacent means. This mechanism comprises a plurality of pairs of feeding wheels 15, each pair being 85 coaxial on a shaft 16. Beneath each wheel 15 is a cooperating roller 17, each pair of rollers being mounted on a shaft 18. The plates 8 and 12 are slotted (Fig. 2) to receive the wheels 15 and rollers 17, the wheels 90 and rollers being adapted to grip the record therebetween.

In Fig. 8 is shown a strip 19 of records, and in Fig. 9 is shown a plurality of individual record cards 20 formed by shearing 95 the strip 19. Each of these records is provided with a pair of locating holes 21 therein in such position as to be in alignment with the wheels 15 during the feeding operation. It will be noted that the greater arcu- 100

ate portion 22 of the periphery of each wheel 15 is narrower than the diameter of the holes 21, relatively wide means 23 being provided at a remaining smaller portion thereof. Power means, hereinafter described, is provided for rotating the several feeding wheels at the same speed in the direction indicated by the arrows. When the strip is fed into the chute 13 against the first pair of wheels 15, the wheels and rollers grip the strip and feed the same along the channel 11 until the narrow wheel peripheries 22 enter the first pair of holes 21. The wheels thereupon ride directly on the rollers 17 through the holes at this time and the strip is not gripped. The movement of the strip therefore stops until a wide portion 23 again engages the strip and restarts the feed. The wheels then continue the feeding until the next pair of holes 21 are engaged.

As illustrated in Fig. 8, the distance between the axes of adjacent wheels 15 is equal to the distance between the adjacent holes 21 of two adjoining records of the strip 19. All three pairs of wheels 15 thereby act simultaneously on the strip in the feeding, stopping and restarting thereof. It should be particularly noted that because of this simultaneous action the feeding means is adapted to feed the records either in strip form or as independent cards as shown in Fig. 9.

The roller shafts 18 extend through vertical slots 24 in the side plates 7 and both ends thereof are supported on bell cranks 25 pivoted at one end 26. Springs 27 connected to the other ends of the bell cranks normally hold the same in a position pressing the rollers 17 resiliently against the wheels 15. A bar 28 is slidably mounted on each side plate 7 and each is provided with three shoulders 29 to engage its three bell cranks. Springs 30 normally hold the bars 28 in the rearward position. The forward ends of the bars 28 are engaged by a cam shaft 31 provided with a handle 32 extending outwardly of the machine. Depressing of the handle 32 is adapted to draw the two bars 28 forwardly and lower the bell cranks 25 and the roller shafts 18. Such movement operates to stop the feeding movement of the records since when the rollers 17 are withdrawn the wheels 15 lose their frictional grip on the strip or record.

Power for operating the machine is derived from a motor M. A pinion 33 on the motor shaft meshes with a gear 34 on a shaft 35. The record feeding mechanism is driven from the shaft 35 as follows (Fig. 4): Spiral gears 36 and 37, shaft 38, flexible connection 39, shaft 40, pinion 41 and gear 42 serve to drive a vertical shaft 43. A bevel gear 44 on this shaft meshes with a bevel gear 45 on the intermediate feed wheel

shaft 16. A gear 46 is mounted on each of the three shafts 16 and these three gears are connected by two idler gears 47. The roller shafts 18 are driven by pinions 48 on such shafts in mesh with the gears 46. It will be understood that the gears 46 are identical and that therefore the shafts 16 are uniformly driven at the same speed. It will also be understood that the circumferential dimension of the feed wheels 15 and the width of the cards 20 are such that one card is fed to each rotation of such wheels.

The feeding operation is substantially as follows:

The front end of the strip (Fig. 8) is placed in the chute 13 into contact with the first pair of feed wheels 15. These wheels feed the strip until the narrow peripheral portions 22 engage in the holes 21. This serves to properly align the strip since the strip will stop with the first pair of holes 21 directly beneath the first pair of feed wheels. When the wide portions 23 engage and restart the strip it is again fed along until the next pair of holes 21 are engaged. As shown in Fig. 8, the holes 21 are spaced a distance exactly equal to the spacing of the shafts 16. Therefore when one pair of wheels engage in a pair of holes the next pair of wheels engage in the next pair of holes, etc. It will also be understood that the peripheral dimension 22 is greater than the distance between two adjacent holes 21. For this reason the strip always has an appreciable dwell after each feeding operation, during which the feed wheels are rotating idly in the holes 21.

By referring to Fig. 9 it will be understood that the mechanism will feed independent cards 20 in the same manner and arrangement as when the same are connected in strip form. When shearing the strip 19 into independent cards, a narrow strip is cut out between each two adjacent records. This operation removes the crease which is formed when the strip is fan folded into pack form.

By referring to the parent application it will be noted that the dwell in the feed of the records permits certain operations incidental to the sensing of the records to be performed.

We claim:

1. A record feeding mechanism comprising the combination of a support for the records, a plurality of feeding wheels relatively spaced along the support with their axes extending transversely to the line of record feed thereon, rollers cooperating with the wheels in a manner to grip the record therebetween and move the same along the support, the greater arcuate portion of the periphery of each wheel being narrower than the diameter of a locating hole in each record in alignment with the wheels during the feeding operation whereby the feeding movement of the record is interrupted by the engaging of the wheel with its roller entirely through

- such hole, means for automatically re-starting the record after a predetermined interruption, the wheels being so relatively located that a record is passed by one feeding wheel to its next adjacent wheel, and means for rotating the wheels at the same peripheral speed.
2. A record feeding mechanism comprising the combination of a support for the records, a plurality of feeding wheels relatively spaced along the support with their axes extending transversely to the line of record feed thereon, rollers cooperating with the wheels in a manner to grip the record therebetween and move the same along the support, the greater arcuate portion of the periphery of each wheel being narrower than the diameter of a locating hole in each record in alignment with the wheels during the feeding operation whereby the feeding movement of the record is interrupted by the engaging of the wheel with its roller entirely through such hole, means for automatically re-starting the record after a predetermined interruption, the wheels being so relatively located that a record is passed by one feeding wheel to its next adjacent wheel, means for rotating the wheels at the same peripheral speed, and a unitary means for stopping the record feed without stopping the rotation of the said wheels by withdrawing all the said rollers from cooperation with their said wheels.
3. A record feeding mechanism comprising the combination of a support for the records, a plurality of pairs of feeding wheels, the wheels of each pair being coaxial and the respective pairs being relatively spaced along the support, rollers cooperating with the wheels in a manner adapted to grip the record therebetween and move the same along the support, the greater arcuate portion of each wheel being narrower than the diameter of locating holes in the records in alignment with the wheels during the feeding operation whereby the feeding movement of the record is interrupted for a predetermined pause by the engaging of the wheels with their rollers entirely through such holes, and means for rotating the wheels in synchronism and re-starting the record at the end of each of said predetermined interruptions.
4. In a mechanism for intermittently feeding records each having a locating hole therein, the combination of a support for the records, a plurality of record feeding means relatively spaced along the support and acting on the records in alignment with said holes therein, the feeding means acting frictionally on the records to pass them along and being so relatively spaced that each record is passed by one of said feeding means onto the succeeding feeding means and being inoperative to feed a record when engaged within said holes, and means operating synchronously with the feeding means for intermit-

tently starting such records after a predetermined pause at said holes.

5. In a mechanism for intermittently feeding records each having a locating hole therein, the combination of a support for the records, a plurality of record feeding means relatively spaced along the support and acting on the records in alignment with said holes therein, the feeding means acting frictionally on the records to pass them along and being so relatively spaced that each record is passed by one of said feeding means onto the succeeding feeding means and being inoperative to feed a record when engaged within said holes, means operating synchronously with the feeding means for intermittently starting such records after a predetermined pause at said holes, and means for stopping the record feed without stopping the operation of the record feeding means.

6. A record feeding mechanism comprising the combination of a support for the records, a plurality of feeding wheels relatively spaced along the support with their axes extending transversely to the line of record feed and their peripheries adapted to frictionally engage the records in line with locating holes therein, the greater arcuate peripheral portion of each wheel being narrower than the diameter of said holes whereby the feeding movement of the record is interrupted when the wheels engage therein, a wider record engaging portion on the periphery of each wheel for restarting each record after a predetermined pause, and means for rotating the wheels, the wheels being so spaced in the direction of feed that the records are intermittently passed from one wheel to the next adjacent wheel.

In testimony whereof we affix our signatures.

LEONARD W. LANGFORD.
